UNITED STATES PATENT OFFICE.

SAMUEL F. STEIN, OF WILLIAMSPORT, PENNSYLVANIA.

SEWING-MACHINE.

1,383,438.

Specification of Letters Patent.

Patented July 5, 1921.

Application filed July 19, 1918. Serial No. 245,781.

To all whom it may concern:

Be it known that I, SAMUEL F. STEIN, a citizen of the United States, of Williamsport, Pennsylvania, have invented Improvements in Sewing-Machines, of which the following is a specification.

The object of my invention is to provide improved means for operating a sewing machine presser foot, which will make unnecessary any special attention of the operator for working it, as is required at certain times, and to such end my invention consists in the presser foot operating mechanism constructed substantially as hereinafter specified and claimed.

In the accompanying drawings.

Figure 1 is a side elevation of a sewing machine embodying one form of my invention, the parts being adjusted for the automatic operation of the presser foot;

Fig. 2 is a vertical section on line 2—2 of Fig. 1;

Fig. 3 is a detail plan view of the foot pedal with switch engaging finger in inactive position.

In making my invention I have had in view the production of mechanism by which the operator, in connection with or as part of the act of starting and stopping the machine (as when the latter is power operated) will cause the depression and lifting of the presser foot automatically, so that no separate act on the operator's part is required, and hence effort and time saved over constructions where the presser foot requires a distinct operation, and yet while accomplishing this desirable result, enabling the independent hand-operation of the presser foot should that be necessary or desirable.

My invention is admirably suited for embodiment in a sewing machine driven by an electric motor, and I have selected for illustrating one application of it, an electric motor driven machine.

Referring to the drawings, 10 designates the presser foot, 11 the presser foot bar, and 12 the box or casing at the end of the sewing machine arm, in which the presser foot bar and the needle bar are mounted, all which parts are and may be of usual construction.

Suitably supported on the upper part of casing 12, as by a strap or bracket 13, is an electromagnet, which, as shown, may be a solenoid 14 arranged so that its core 15 extends vertically, and which at its upper end is secured to a horizontally extending thin,

light elastic bar or strip 16, that reaches to a point above the upper end of the presser foot bar, so as to rest thereon, and which acts to force the presser foot down upon the goods being sewed, when the solenoid is energized and pulls its core downward. By making the strip 16 elastic, it is a spring that yieldingly holds the presser foot against the goods and thus allows the customary short, vertical reciprocation of the presser foot during sewing.

A light spring 17 coiled around the presser foot bar, and bearing at its lower end against the bottom of the casing 12 and at its upper end against a projection 18 on said bar, lifts the presser foot when the solenoid is deenergized.

A convenient way of adjusting the pressure exerted by the spring 16 on the presser foot is to provide a stop screw 19 at the bottom of the solenoid which enters the hole thereof, in position to be engaged by the bottom of the core 15, when the latter descends, and which, by vertical adjustment determines or fixes the limit of downward movement of the core, and, hence, the amount of force exerted on the spring 16.

It may be desired, for various reasons, to enable the presser foot to be operated, in the usual manner, by hand, I, therefore, retain the usual lifting lever 20, pivoted to the casing 12, and having a cam 21 adapted to act on the projection from the presser foot bar which, in the case shown in Fig. 1, may be the lifting spring engaging projection 18. When the magnet is being used, the lifter cam 21 must be in its lowermost position so that it will not prevent the descent of the presser foot under the pull of the magnet, and yet, to employ the lifter cam, which characteristically works against a spring that tends to lower the presser foot, a spring must be employed, whose tendency is downward, the operative conditions in the use of the magnet and the lifter cam being thus reversed, since with the magnet, the presser foot is depressed against spring pressure and with the lifter cam it is lifted against spring pressure, I can reconcile these conflicting conditions or requirements in various ways. Thus, when the construction shown in Fig. 1 is employed, the spring 16 may be made to serve as the presser foot lowering spring, by shifting it and the solenoid core downward and thereby carrying the presser foot down to goods engaging position, which can readily be done, as the coil

100

105

110

spring 17, being the weakest, will compress. The presser foot projection 18 will thus be brought down to engage the lifter cam when in its lowest position, so that when said cam is rocked to its highest position it will, by acting on the projection 18, lift the presser foot against the force of the spring 16. A simple device for thus converting the spring 16 into a depressing spring is shown in Figs. 5 10 1 and 2, said device consisting of a screw 22 in a strap or bracket 23 projecting above the casing 12, and adapted to bear upon a strip or plate 24 attached to the solenoid core, and extending horizontally above the 15 spring 16. Said strip 24 also serves to prevent turning of the solenoid core and lateral displacement of the spring 16, since it is straddled by side legs of the bracket 23.

The same end can be accomplished by 20 shifting the coil spring 17 from below the projection 18 to above the latter so that it exerts a downward pressure on the presser foot. By making the projection 18 a simple, radial pin, the transposition of the coiled 25 spring 17 can be effected simply by revolving it to move it past the pin by a sort of screwing operation. There are notches 170 in the last coils of the spring to interlock with the pin to prevent accidental turning 30 of the spring.

Where, as in the construction shown in the drawings, the sewing machine is driven by an electric motor, I place the solenoid in circuit with a switch that is operatively 35 connected or associated with the controller of the machine motor.

For convenience of illustration, the motor is shown drivingly connected with the sewing machine by a belt B that connects a 40 pulley M on the motor shaft, with a pulley P on the sewing machine shaft, pulleys and belt being shown in dotted lines.

The controller and switch are shown somewhat diagrammatically in the drawings, the controller being in the customary 45 form of a treadle 25, that successively cuts out of or in circuit, as it is depressed or raised, a series of resistances 26, so as to vary the speed of the motor and the machine.

50 Pivoted to swing beneath the treadle 25, is an arm 27 that carries a normally open switch 28 in circuit with the solenoid, and suitably electrically connected with the circuit which supplies the motor, and said 55 switch 28 is under control of a finger 29 mounted on the treadle 25, and movable, so that it may be placed, at the will of the operator, either in position to close the switch 28, when the treadle is depressed or 60 in a position where it will not act on said switch. The finger 29 is pivoted at one end to the treadle so that it may be swung from a position to act on the switch 28. This 65 enables the operator to run the machine without automatically depressing the presser

foot on the goods, which, as well known, is necessary in some sewing operations, as at the beginning and end of the seam to tack, to prevent the unraveling of the stitching. It also enables the hand control of the presser 70 foot, by not closing the circuit through the solenoid. The finger 29 is pivoted to the treadle in position to be struck by the foot of the operator for shifting its switch engaging end into and out of switch engaging 75 position. The switch 28 is situated in a depression in the arm 27 so that treadle 25 cannot touch the switch to close it. When the finger 29 is in position, by the depression of the treadle, to engage the switch 28, I 80 prefer that such engagement shall not take place until after the treadle has first moved far enough to cut the motor into circuit, as this enables the sewing machine to run at the beginning of the sewing operation with 85 the presser foot raised, which is a desirable feature.

What I claim is:

1. A sewing machine having a presser foot, a motor for driving the machine, and 90 automatic means for depressing the presser foot associated with the motor control mechanism.

2. A sewing machine having a presser foot spring that normally exerts a lifting 95 force, a motor for driving the machine, and automatic means for moving the presser foot against such force, operatively associated with the motor control mechanism.

3. In a sewing machine, the combination 100 of a presser foot, an electro-magnet, and means independent of the feed dog for moving the presser foot by said magnet.

4. In a sewing machine, the combination 105 of a presser foot, an electric motor, a treadle for controlling the motor circuit, an electro-magnet, a treadle controlled circuit including said magnet and means for moving the presser foot by the magnet.

5. In a sewing machine, the combination 110 of a presser foot, an electro-magnet, and means for moving the presser foot by said magnet including an elastic member between the magnet and the presser foot.

6. A sewing machine having a presser 115 foot, hand actuated means to control the depression of the presser foot, automatic means to depress the presser foot, and means operable at will to prevent the action of the automatic means whereby the machine may 120 be run without the presser foot being depressed, and alternately under hand manipulation and automatic operation of the presser foot.

7. A sewing machine having a presser 125 foot, a motor for driving the machine, automatic means for moving the presser foot and successively acting controlling means for motor and presser foot.

SAMUEL F. STEIN,
